(57) **CLAIM**

The ornamental design for a putter face, as shown and described.

DESCRIPTION

FIG. 1 is a front perspective view of a putter with the putter face;

FIG. 2 is a front view of the putter with the putter face;

FIG. 3 is a rear view of the putter with the putter face;

FIG. 4 is a heel side view of the putter with the putter face;

FIG. 5 is a toe side view of the putter with the putter face;

FIG. 6 is a top view of the putter with the putter face; and,

FIG. 7 is a bottom view of the putter with the putter face.

The broken lines shown are for illustrative purposes only and form no part of the claimed design.
